(57) **CLAIM**

The ornamental design for a fishing lure, as shown and described.

DESCRIPTION

FIG. 1 is a perspective front view of the fishing lure;
FIG. 2 is a front view of the fishing lure;
FIG. 3 is a rear view of the fishing lure;
FIG. 4 is a left view of the fishing lure;
FIG. 5 is a right view of the fishing lure;
FIG. 6 is a top view of the fishing lure; and,
FIG. 7 is a bottom view of the fishing lure.
The broken line showing of environment in the drawings is
included for the purpose of illustrating only and forms no part
of the claimed design.
